UNITED STATES PATENT OFFICE.

PAUL C. PINCHES, OF BROOKLYN, NEW YORK, ASSIGNOR TO LEE S. SMITH & SON MANUFACTURING COMPANY, OF PITTSBURGH, PENNSYLVANIA, A CORPORATION OF PENNSYLVANIA.

SHADE-GUIDE.

1,246,999.

Specification of Letters Patent. Patented Nov. 20, 1917.

Application filed February 12, 1917. Serial No. 148,019.

To all whom it may concern:

Be it known that I, PAUL C. PINCHES, a citizen of the United States, and a resident of Brooklyn, in the county of Kings and State of New York, have invented a new and useful Improvement in Shade-Guides; and I do hereby declare the following to be a full, clear, and exact description thereof.

My invention relates to shade guides for matching tooth cement, which cement is used as a filling for a tooth, and which after insertion has the appearance of a good natural tooth.

The shade guides or samples proper are formed from the different cements, and are designated for each particular cement tint, and heretofore in the manufacture of matching tooth cement various processes have been used, such as supporting the shade samples on suitable devices and designating the same by characters in order to determine the best sample to be used when placing the same in position, so that the desired shade of tooth cement could be thereby selected from stock or ordered. In another process, by the use of such samples, the different shades or tints for matching were supported on devices and placed in water, contained in a bottle, so as to wet the same, in order to keep such samples in a moistened condition and for changing the tints, but this process is unsatisfactory for the reason that the water rapidly evaporates from the sample when removed therefrom, so that the shade of the cement when comparatively or altogether dry will differ radically from its appearance when in a moist condition. This process also allows the water to evaporate, by reason of opening the bottle constantly, while such water will also become stagnant, and by reason of being shipped in such bottles, the bottles are liable to break thereby exposing the samples to the air and spoiling the same. In addition to the above objections, an equally important one is the fact that when samples of cement shades are lifted from the water in which they are contained for the purpose of matching teeth in the mouth, the water is likely to drip on the clothing of the patient, and great difficulty is experienced in segregating the various shades before the change resulting from exposure to atmospheric conditions.

The object of my invention is to provide a shade guide for matching tooth cement,

which will be cheap, simple and efficient in its construction, will be so formed as will retain the shade of cement material from which it is formed, at all times, devices for enabling it to be designated, will not be required to be placed in water or other liquid to moisten the same and change the tint, but one which will overcome all of the objections and difficulties heretofore found in making and handling such samples.

To these ends my invention consists, generally stated, in the novel form of a shade guide for matching tooth cement, as herein-after more particularly set forth or described.

To enable others skilled in the art to which my invention appertains, to construct and use my improved shade guide for matching tooth cement, I will describe the same more fully, referring to the accompanying drawing, in which—

Figure 1 is a front elevation of a shade guide made in accordance with my invention; and

Fig. 2 is a section of the same on the line 2—2 of Fig. 1.

Like symbols of reference herein indicate like parts in each of the figures of the drawing.

As illustrated in the drawing, 1 represents my improved shade guide for matching teeth, which comprises a container 2 for being filled with the water or other moistening liquid to be used, and is of flat and substantially oval shape. This container 2 can be composed of vulcanized rubber, celluloid, metal, or other suitable material, and cast or formed to shape in any suitable manner, so as to form the receptacle 3 within the same and a filling opening 4 through the front wall of the same. This opening 4 is threaded, and a threaded cap 5 engages the same and acts as a cover for said opening, as well as a handle for the device. Formed on the periphery of the upper oval edge of the container 2 are a series of tubular extensions 6, which communicate with the receptacle 3 in the container 2 and are provided with the enlargements 7 at the outer ends of the same. Connected around each of the extensions 6 is a rubber or other flexible tube 8, which has its one or inner end fitting over and around the enlargements 7 on said extensions and its other end is adapted to carrying the shade guide or sample 9. This

shade guide or sample is made from the usual cement, and such cement is formed of the usual materials which are put up in the form of a powder and mixed with phosphoric acid into a paste. The shade guide or sample can be formed in any suitable manner and into the shape of a tooth, or into any other desired shape and by any suitable means. After being so formed the shade guide or sample is provided with a suitable transparent covering which can be formed from any suitable material such as the glaze or glass container 10 and which can be formed in any suitable manner to conform to the shape of the shade guide or sample. If desired, such container can be formed slightly larger than the guide or sample for the purpose hereinafter described. This container 10 is provided with a lip 11 at its open or lower end, and each of the tubes 8 are adapted to carry a container having a shade sample 9 therein by the lips on the containers fitting within the outer ends of the said tubes.

These shade samples 9 can be placed within their coverings or containers 10 in any suitable manner, and if desired can be so formed as to provide a space 13 around the same for the water from the container 2 to circulate, as hereinafter described.

In the use of my improved shade guide 1, with the parts assembled as above described, and water being placed within the receptacle 3 of the container 2 through the opening 4, it will be obvious that the samples 9 within the coverings or containers 10 will be kept moistened through the medium of the water from the container 2 passing through the tubes 8 and coming in contact with the ends of such samples or in passing around the same through the space 13 between such samples and the said coverings.

It will thus be seen that in filling a tooth with cement it is very often difficult to obtain the proper color to match with the tooth to be filled or the adjacent tooth when the cement serves in making a tooth, and one is very liable to get the filling either darker or lighter than the tooth itself; but with the invention described, this liability of error is reduced to a minimum. In the usual processes of forming these shade guides or samples, they bleach out unless used immediately, while by the use of my improved guide the translucency of the material or sample is preserved and maintained, and there is no liability of air coming in contact with the same to change the shade or tint. By the invention described the shade sample so covered would present the moist appearance at all times without the necessity of keeping the same immersed in water or other liquid by hanging the same from devices, and yet the covering will be so strong and hard as will enable the guides carrying the samples

to be packed together or kept in trays for handling or use by the supply house or dentist.

It will also be seen that my improved shade guide will enable each sample to be segregated from the other, so that the proper sample can be determined for matching by simply bending back the adjacent samples to the one being matched, while such guide is also easily and convenient to handle, is sanitary, can be kept clean, and the parts being detachable can be readily and quickly set in place or taken apart for the placing of the samples in position or for any other purpose.

It will be obvious that my improved shade guide can be formed of materials other than those described and that various modifications and changes in the design and construction may be resorted to without departing from the spirit of the invention or sacrificing any of its advantages.

What I claim as my invention and desire to secure by Letters Patent is—

1. A shade guide, comprising a receptacle for a moistening liquid, and a plurality of tubes connected at one end to said receptacle and having matching cement tooth samples at their other ends for contacting with said liquid through said tubes, said samples having a transparent covering over the same.

2. A shade guide, comprising a receptacle for a moistening liquid, and a plurality of flexible tubes connected at one end to said receptacle and having matching cement tooth samples at their other ends for contacting with said liquid through said tubes, said samples having a transparent covering over the same.

3. A shade guide, comprising a receptacle for a moistening liquid, a tube having its inner end connected to said receptacle, and a matching cement tooth sample at the outer end of said tube for contacting with said liquid through said tube, said sample having a transparent covering over the same.

4. A shade guide, comprising a receptacle for a moistening liquid, a flexible tube having its inner end connected to said receptacle, and a matching cement tooth sample at the outer end of said tube for contacting with said liquid through said tubes, said sample having a transparent covering over the same.

5. A shade guide, comprising a receptacle for a moistening liquid, a flexible tube having its inner end connected to said receptacle, and a matching cement tooth sample at the outer end of said tube for contacting with said liquid through said tube, and a covering for said tooth to prevent the atmosphere reaching the same, said covering permitting viewing of said tooth.

6. A shade guide, comprising a receptacle for a moistening liquid, a matching cement tooth sample, means for conveying the liquid

from said receptacle to said sample, and means for preventing the evaporation of said liquid, said means allowing viewing of said tooth.

5 7. A shade guide, comprising a receptacle for a moistening liquid, a matching cement tooth sample having a transparent covering over the same, and means communicating with said receptacle and said sample for con-

veying the liquid from said receptacle to 10 said sample.

In testimony whereof, I the said PAUL C. PINCHES, have hereunto set my hand.

PAUL C. PINCHES.
